UNITED STATES PATENT OFFICE.

GEORGE CHARLTON, OF DETROIT, MICHIGAN, ASSIGNOR OF ONE-THIRD TO ERNEST CARTER AND ONE-THIRD TO FRANK IBBOTSON, BOTH OF DETROIT, MICHIGAN.

STIPPLER.

1,369,163.

Specification of Letters Patent. Patented Feb. 22, 1921.

Application filed May 17, 1920. Serial No. 381,820.

To all whom it may concern:

Be it known that I, GEORGE CHARLTON, a citizen of the United States of America, residing at Detroit, in the county of Wayne 5 and State of Michigan, have invented certain new and useful Improvements in Stipplers, of which the following is a specification, reference being had therein to the accompanying drawings.

10 The primary object of my invention is to provide a stippling instrument or tool that may be advantageously used by photographers and artists for retouching photographic negatives, prints and pictures, the instrument including a pencil or stylus and novel means for imparting movement thereto, so that lines may be softened, shadows raised, and the density of negative portions increased or decreased by inscribed or overlapping circles in contradistinction to dots, 15 lines, and the hooks generally used.

Another object of my invention is to provide an instrument of the above type including a tiltable member that may be adjusted 20 to increase or decrease the size or diameters of circles inscribed by the instrument, the tiltable member forming part of the power transmission mechanism within the instrument and even though the instrument is in 25 operation, the tiltable member may be easily and quickly adjusted.

A further object of my invention is to provide a stippler wherein the parts are constructed with a view of reducing the cost of 30 manufacture and at the same time retaining those features by which durability and ease of assembling are secured. With such ends in view my invention resides in the novel construction to be hereinafter considered 35 and then claimed.

Reference will now be had to the drawing, wherein—

Figure 1 is a side elevation of the instrument, partly broken away;

40 Fig. 2 is a longitudinal sectional view of the same;

Fig. 3 is an enlarged cross sectional view taken on the line 3—3 of Fig. 2;

Fig. 4 is a similar view taken on the line 45 4—4 of Fig. 2 and

Fig. 5 is a similar view taken on the line 5—5 of Fig. 2.

To put my invention into practice, I provide a tubular handle or barrel 1, and in the 55 inner end thereof is mounted a bearing 2 for

a drive shaft 3 which has its outer end provided with a stop flange 4 abutting the bearing 2, and to the outer end of said drive shaft may be coupled a driven shaft (not shown).

60

Mounted in the outer end of the handle or barrel 1 is the inner tubular end 5 of a socket member 6 containing a ball member 7 which has a universal movement in the socket member. Mounted in the ball member 7 is 65 a wabbler sleeve 8 provided with a convex head or stop 9 abutting the ball and socket members. The outer end of the wabbler sleeve is split or slotted, as at 10, and exteriorly screwthreaded, as at 11. Adjustable 70 on the threaded portion of the wabbler sleeve is a cap 12 that may be held in adjusted position by a jam nut 13 on said wabbler sleeve. The cap 12 is adapted to contract the split or slotted end of the 75 wabbler sleeve about a stylus 14 or other member placed in said wabbler sleeve, so that the stylus will be firmly held during a wabbling movement of the sleeve.

In the inner end of the wabbler sleeve 8 80 is fitted a pin 15 which extends into an eye 16 at the outer end of a tiltable fulcrum member 17 fulcrumed on a transverse pin 18 mounted in the bifurcated inner end 19 of the drive shaft 3. This bifurcated inner 85 end of the drive shaft also accommodates a flat spring 20 held in position by a transverse pin 21 carried by said drive shaft. One end of the flat spring 20 engages the inner end of the tiltable fulcrum member 17, 90 and tends to hold said member so that no circles will be produced, but said member may be shifted from this position, against the action of said spring, to cause the stylus 14 to produce circles of different diameter. 95 The spring 20 is housed within a drive shaft sleeve 22 and one end of said spring protrudes from the sleeve to engage the member 17.

Slidable on the bifurcated inner end of 100 the drive shaft 3 is a slide ring 23 having its outer walls engaging the inner walls of the tubular handle or barrel 1. Mounted in the slide ring 23 are opposed screws or pins 24 extending through longitudinal slots 25 105 in the handle or barrel 1, and said screws or pins are carried by a slide sleeve 26 shiftable longitudinally of the handle or barrel. The slide sleeve 26 may be knurled or otherwise roughened to facilitate movement of 110

the sleeve on the handle or barrel and when said sleeve is shifted toward the inner end of the handle or barrel the slide ring 23 is moved on the bifurcated end of the drive shaft and engages and tilts the inner end of the fulcrum member 17. As shown in Fig. 2 the stylus 14 is practically in the axis or in alinement with the drive shaft 3, but when the inner end of the member 17 is 10 pressed into the bifurcated end of the drive shaft 3, by the slide ring 23, the inner end of the stylus is shifted to one side of the axis of the drive shaft, thereby placing the stylus at an angle so that when the drive shaft is revolved the stylus point will produce circles.

It is obvious that the handle or barrel may be graduated so that the slide sleeve may be shifted a desired distance and thus 20 permit the operator of the instrument to produce predetermined circles, which by manipulation of the instrument, may be inscribed or overlapping.

It is thought that the utility of my instrument will be apparent without further description, and while in the drawing, there is illustrated a preferred embodiment of the invention, it is to be understood that the structural elements are susceptible to such 30 variations and modifications as fall within the scope of the appended claims.

What I claim is:—

1. An instrument of the character described comprising a tubular handle, a drive shaft extending therein and having an inner bifurcated end, a wabbler sleeve extending into the outer end of said handle and adapted for holding the stylus, a universal connection between said wabbler sleeve and 35 said handle, a tilttable member fulcrumed in the bifurcated end of said drive shaft and having connection with said wabbler sleeve, and means slidable on said handle adapted for adjusting said tilttable member so as to place said wabbler sleeve at an angle to the axis of said handle.

2. An instrument as characterized in claim 1, wherein said means includes a sleeve on said handle and a ring on the bifurcated

end of said drive shaft, said ring having 50 connection with said sleeve through the walls of said handle.

3. An instrument of the character described comprising a tubular handle, a drive shaft journaled in the inner end of said handle and having a bifurcated end therein, a wabbler shaft having a universal connection with the outer end of said tubular handle, a tilttable member in the bifurcated end of said drive shaft and having connection with said wabbler sleeve, means in the bifurcated end of said drive shaft normally pressing against said tilttable member to maintain said member at an angle to the axis of said drive shaft, and adjustable 60 means carried by said handle for engaging said tilttable member to reduce the angularity of said member relative to said drive shaft.

4. An instrument as characterized in 70 claim 3, wherein the last mentioned means includes a ring slideable on said drive shaft and operable from outside of said handle.

5. An instrument of the character described comprising a handle, a drive shaft 75 extending therein, a wabbler sleeve extending into said handle and adapted for holding a stylus, a universal connection between said wabbler sleeve and said handle, a tilttable member supported by said drive shaft 80 in said handle and having connection with said wabbler sleeve, and means on said handle adapted for adjusting said tilttable member so as to place said wabbler sleeve at an angle to the axis of said handle.

6. A stippler comprising a stylus, a drive shaft, a tilttable member carried by said drive shaft and articulated with said stylus for imparting movement to said stylus, and shiftable means on said drive shaft for tilting said member to regulate the movement of said stylus.

In testimony whereof I affix my signature in the presence of two witnesses.

GEORGE CHARLTON.
